(57) **CLAIM**

The ornamental design for a digging element for a trenching device as shown and described.

DESCRIPTION

FIG. 1 is a three-dimensional view of a digging element for a trenching device according to the present invention; FIG. 2 is a left side view of the digging element for a trenching device of FIG. 1;

FIG. 3 is a right side view of the digging element for a trenching device of FIG. 1;

FIG. 4 is a front view of the digging element for a trenching device of FIG. 1; and,

FIG. 5 is a rear view of the digging element for a trenching device of FIG. 1.
